UNITED STATES PATENT OFFICE.

DAVID MANUEL, OF HYDE PARK, MASSACHUSETTS, ASSIGNOR TO HIMSELF
AND IRA L. BENTON, OF SAME PLACE.

FREIGHT-CAR DOOR.

SPECIFICATION forming part of Letters Patent No. 416,793, dated December 10, 1889.

Application filed December 1, 1888. Serial No. 292,377. (No model.)

To all whom it may concern:

Be it known that I, DAVID MANUEL, of Hyde Park, in the county of Norfolk, State of Massachusetts, have invented a certain 5 new and useful Improvement in Freight-Car Doors, of which the following is a description sufficiently full, clear, and exact to enable any person skilled in the art or science to which said invention appertains to make 10 and use the same, reference being had to the accompanying drawings, forming part of this specification, in which—

Figure 1 is a side elevation showing a portion of a freight-car provided with my improvement; Fig. 2, a longitudinal transverse section taken on line $x-x$ in Fig. 1; Fig. 3, an enlarged sectional view showing the track and bonnet; Fig. 4, a horizontal section enlarged, showing one of the clamping-plates; 20 Figs. 5 and 6, enlarged horizontal sections showing the carriages in top plan view and in different positions on the track; Fig. 7, a vertical transverse section, the carriage being represented in end elevation; Fig. 8, a 25 front elevation of one of the carriages; Fig. 9, a vertical longitudinal section of the same, and Fig. 10 a sectional view showing one of the wedge-pieces on the front edge of the door.

Like letters and figures of reference indicate corresponding parts in the different figures of the drawings.

My invention relates especially to means for hanging a freight-car door, whereby it 35 may be automatically forced against the casing when closed and rendered practically airtight; and it consists in certain novel features, as hereinafter fully set forth and claimed, the object being to produce a simpler, cheaper, and more effective device of 40 this character than is now in ordinary use.

The nature and operation of the improvement will be readily understood by all conversant with such matters from the following 45 explanation.

In the drawings, A represents the car-body, and B the door. The edges of the door-casing are beveled, as shown at b , and the corresponding edges of the door B beveled to 50 conform thereto, so that said door will fit closely into the casing when closed.

A longitudinally-arranged track C is secured to the side of the car above the door-casing, said track being formed in two sections (see Fig. 2) and consisting of an outside or bearing rail d , connected by horizontal braces f with a supporting-plate g , which is bolted to the body of the car. A hood h is secured to the under side of said track to prevent the water from being driven in between the top of the door and casing. 55

Two chambers or pockets D F (see Fig. 2) are formed in the body of the car above the door-casing at the forward and rear ends thereof, respectively, the forward ends of the 60 two sections of track C being curved and extended into said chambers.

The carriages H K consist, respectively, of two plates i k , secured together by bolts l , the central portion of said plates being extended 70 vertically to form a chamber m , (see Fig. 9,) in which is journaled two transversely-arranged rolls p . The rolls p rest upon a ball r , which projects through a slot or opening t , formed centrally in the lower plate k , and 75 bears upon the outer rail d of the track, as shown in Figs. 7 and 9.

Projecting downward from the plate k at the outer edge of the opening t are two studs v , on each of which a horizontally-arranged 80 wheel w is fitted to revolve, said wheels being so disposed that they bear against the outer face of the rail d when in use. At the opposite side of the opening t a similar stud z is disposed, said stud being provided in like 85 manner with a wheel y , which is adapted to bear against the inner face of the rail d , the purpose of said wheels being to prevent the carriage from tipping or swaying laterally on the track. 90

A hanger consisting of a metallic plate L is bolted by its lower end to the forward upper corner of the door B, the upper end of said hanger being bent at right angles to the body thereof, forming an arm 15, which projects inward over the track C. A vertical stud 25, formed centrally on the plate i of each carriage H K, is fitted to revolve in a central opening in said arm 15. An outwardly-projecting horizontally-arranged semicircular 95 flange 35 is formed on the plate i , said flange working in a groove 45, (see Fig. 7,) formed 100

in the inner face of said hanger, the purpose of said flange being to hold the carriage in a horizontal position and thereby prevent the stud 25 from binding in the hanger-arm 15.

- 5 A rearwardly - projecting horizontally - arranged bar 55 is secured to the upper rear corner of the door B, and the lower end of a similar hanger M, which is connected with the carriage H, is adjustably secured to the outer end of said bar by bolts 65, passing through horizontal slots 75 in said hanger, as shown in Fig. 8. A plate 85, (see Fig. 10,) provided with a diagonally-arranged inwardly-projecting arm 95, is secured to the lower front corner of the door B, said arm being adapted to enter a corresponding socket 14 in the body of the car and assist in clamping or forcing the door tightly against its casing. To the opposite lower corner of the door is adjustably secured a rearwardly-projecting bar 24, provided on its outer end with a cam-shaped stud or projection 34, (see Fig. 4,) adapted to engage a roll 44 on a bracket 54, secured to the body of the car, and assist in forcing the door inward against the casing when closed. A lever P is pivoted at 64 to the face of the door, one arm 74 projecting downward and passing through a diagonally-arranged loop 84 on the door, the lower end 30 of said arm being provided with a handle 94, as shown in Fig. 1. The horizontal arm 13 of said lever passes through a guide-loop 23 on the forward edge of said door, and is provided with a hook 33 on its outer end. A latch 35 43 is pivoted to the body of the car and passes through a guide-loop 53, its outer or free end being provided with a hook 63, adapted to engage the hook 33 on said lever and secure the door when closed. A longitudinally-arranged water shed or hood R (see Fig. 3) is secured by braces 73 to the top of the car to protect the track and carriages.

In the use of my improvement, the door being suspended from the track C, as described, it will be seen that the only bearing-points of the door upon said track are the balls r, which renders it exceedingly easy to move said door. The door being open, if it is desired to close the same the handle 94 of 45 the lever P is grasped and the door pushed forward by means of said handle. The carriages H K travel on the rail d of the track until they reach the curved portion thereof, leading into the chambers D F, when the 50 guide-wheels w y of said carriages respectively direct the course of said carriages into said chambers, and thereby force the upper portion of the door inward against the beveled casing b. At the same time the 55 curved arm 95 on the lower portion of the door enters the socket 14 in said casing, and the stud 34 at the rear thereof engages the roll 44 on the bracket 54, which forces the lower edge of the door tightly against the casing. The hook 33 on the lever P has meanwhile engaged the latch 43, causing the same to be elevated until it has passed over said

hook and securely locked the door in a manner that will be readily understood by all conversant with such matters without a more explicit description. 70

Having thus explained my invention, what I claim is—

1. In a device of the character described, a horizontally-arranged track secured to the car above the door-casing, said track being constructed in two sections, a chamber formed in the body of the car at the forward end of each section, said track projecting into said chambers, and a door suspended by carriages 80 on said track, said carriages being so disposed that they will enter said chambers and force the door against the casing when closed, substantially as set forth.

2. In a device of the character described, 85 the combination of a car provided with a beveled door-casing, a horizontal track disposed above said casing and constructed in sections, a chamber in the car-body at the forward end of each section, and a door provided with 90 beveled edges and suspended from said track by pivoted carriages which enter said chambers when the door is closed, substantially as and for the purpose specified.

3. In a device of the character described, 95 the car A, having the beveled casing b, and socket 14, in combination with the sliding door B, having its edges beveled to fit said casing and provided with the plate 85, having the arm 95, which enters said socket and 100 forces the door against the casing when closed, substantially as specified.

4. In a freight-car door, the bar 24, secured to said door and provided with the cam projection 34, in combination with the bracket 105 54, secured to the car-body and provided with the roll 44, for engaging said projection and forcing the door against the casing, substantially as set forth.

5. In a device of the character described, 110 the car A, provided with the chambers D F, casing b, and track C, in combination with door B, suspended on said track by carriages H K, and the hood R, disposed on the car above said track, substantially as described. 115

6. In a device of the character described, the car A, provided with the beveled casing b and the chambers D F, in combination with the track C, projecting into said chambers, the door B, suspended by carriages H 120 K on said track and having its edges beveled to conform to said casing, and the hood h on said track, all being arranged to operate substantially as described.

7. In a device of the character described, 125 the combination of a car provided with a door-opening, and a single-rail horizontal track disposed in two sections above said door, a chamber in the car-body at the forward end of each track-section, a door provided with hangers, and carriages mounted on said track by means of balls and rolls, 130 said carriages being pivoted to said hangers and so disposed as to enter said chambers

when the door is closed, substantially as specified.

8. In a device of the character described, the combination of a car provided with a horizontal single-rail track disposed in two sections above the door-casing, a chamber in the car-body at the forward end of each track-section into which said track projects, carriages comprising a chambered body in which two rolls bearing upon a ball are journaled, and a door provided with hangers in which said carriages are pivoted in position to enter said chambers when the door is closed, substantially as set forth.

15 9. In a device of the character described, the carriages H K, comprising the plates i k, forming the chamber m, the rolls p, journaled therein, the ball r, projecting through the slot t, and the guide-wheels w y, in combination with the car A, provided with the track C and chambers D F, and the door B, provided with the hangers L M, to which said carriages are pivoted, substantially as specified.

10 10. In a device of the character described, the door B, provided with the hanger L, and

adjustable hanger M, having the grooves 45, in combination with the car A, provided with the track C and chambers D F, and the carriages H K, pivoted to said hangers and provided with the circular flanges 35, working in 30 said grooves, substantially as and for the purpose specified.

11. In a device of the character described, the combination of the car A, provided with a beveled door-casing, the track C, having the 35 rail d and projecting into chambers D F, formed in said car, the door B, provided with hangers L M, the carriages C, pivoted to said hangers and adapted to travel on said track by means of the balls r, the plate 85, having 40 the arm 95, adapted to enter the socket 14, the bar 24, provided with the cam projection 34, for engaging the roll 44, the lever P, pivoted to said door and having the hook 33, and the latch 43, for engaging said hook, all being arranged to operate substantially as set forth.

DAVID MANUEL.
